UNITED STATES PATENT OFFICE.

JOHN T. HILL, OF BERKELEY, CALIFORNIA, ASSIGNOR TO AUTOMATIC LOCK AND CLOSER COMPANY, OF OAKLAND, CALIFORNIA, A CORPORATION OF FLORIDA.

DOOR CLOSER.

Application filed April 9, 1923. Serial No. 630,753.

This invention relates to door closers, and especially to closers for refrigerators of a size that operatives go into in carrying goods in and out.

5 In such refrigerators it is important that the doors be closed rapidly and completely, a few seconds' delay in so doing involves a loss of cold air from within, by interchange with the warmer air from without, with consequent injury to the contents of the refrigerator by moisture, due to the condensation of the admitted warm air, causing resultant mold and other germ action.

10 Refrigerators of the above class are necessarily air-tight, hence, when a door is rapidly closed, the air within the refrigerator is compressed by the door on nearing its closed position, which compressed air tends to cause a rebound of the door and permitting it to remain open a crack, or to allow it to complete its closing very slowly; in either case resultant loss or damage exists as above stated. Hence, a closing device must have such strength that it will overcome the air 15 compression noted and effect a rapid and complete closing of the door.

It is the chief object of the present invention, to produce a door closer that will fulfill the above requirements and overcome the 20 objections named.

Other objects and the features of construction, will appear in the subjoined description of the accompanying sheet of drawings, in which:

25 Figure 1 is a top view, showing a portion of a refrigerator door and its jamb and the track member in section, and the closer in position with part of the same broken away to show the spring.

30 Figure 2 is a view from the front of a refrigerator door and with the closing apparatus applied, all the parts being in elevation.

Figure 3 is an elevation of the pintle member of the closer.

35 Figure 4 is a top view of the bearing member of the closer supporting the pintle member.

Figure 5 is a top view of the spring shown 40 on a larger scale than the other figures.

Referring to the drawing and the figures thereof:—A refrigerator door 1 is hinged to its jamb 2 in any ordinary manner as by the hinge 3. Mounted on the jamb 2 is the bearing member, which, in the present instance

is of sheet metal, formed with a base 4 and two wings 5 bent up therefrom at approximately right-angles, to form bearing standards. The base is secured to jamb by lag screws 6. The wings or standards 5, are preferably of semi-circular shape, so that the blank from which they are bent may be of a near circular shape. The two wings are each perforated with a round hole 7, in register with each other, and which holes serve 65 as a bearing for a pintle 8 (Fig. 3), whose function will be presently described.

9 is a coiled spring of flat steel and has its inner end formed into a square socket 10, and its outer end extended in a straight portion 11. The spring is of a size to fit or be housed within the space between the wings 5, with the straight portion 11 secured upon the base 4, and the axis of the square hole 10 in register with that of the holes 7 in the wings. 75

When the parts are in this position the pintle 8 may be inserted through the holes of the wings and engage the socket 10. The pintle, it will be observed is square but with its corners rounded or chamfered so that it 80 may be passed through the holes 7, which are just too small to pass the full square of the pin. A short portion of the pin as at its end 12, has its corners intact, and this prevents its dropping through the holes in the wings. 85

An arm 13 has a square socket at one end adapted to fit over the square end 12 of the pin and engage the same, thereby connecting it with the spring 9. The other end of the arm is forked and supports a ball-bearing roller 14. This roller travels over a track 15 secured to the door, as the door swings open or shut. The track is of channel form, thus permitting travel of the roller longitudinally but preventing lateral displacement thereof.

In operation, when the door is swung open, the arm swings outward and winds or coils the spring, which, through its resiliency and reaction, immediately closes the door as soon as the latter is released. A greater or less tension of the spring may be obtained by withdrawing the arm 13 by hand from its track, and inserting a rod or other instrument into one of the holes 16 near the lower end of the pintle member. The rod may then be allowed to bear against the jamb to prevent the turning of the pintle, and the arm removed and replaced 90 degrees in one 105 110

direction or the other as the case may be. Disengagement of the instrument from the pintle, allows the arm to return to its normal position and the roller to retrack.

5 The foregoing apparatus constitutes a very simple and efficient door closer. There are only four essential parts, to wit:—the base or bearing member, the spring member, the pintle member, and the arm member, and to the latter is added two contributing parts, to wit:—the track member and the roller member. These few parts are all of extreme simple construction and not liable 10 to get out of order, are efficient in operation and cheap to manufacture.

From the foregoing description taken in connection with the accompanying drawings, the advantages of the construction and method of operation will be readily understood by those skilled in the art to which the invention appertains, and while I have described the principle of operation, together with the device which I now consider to be the best embodiment thereof, I desire to have 20 it understood that the device shown is merely illustrative and that such changes may be made when desired, as fall within the scope of the appended claim.

Having thus described my invention, what

I claim as new and desire to secure by Letters Patent of the United States, is the following:

In a door closer, a door engaging arm having at one end a roller, a track for the door over which said roller may travel, the opposite end of said arm provided with an opening, a pintle for mounting the arm through said opening, a bracket comprising a single sheet of metal having bent up outstanding and spaced-apart bearing flanges, openings 35 in said flanges to receive said pintle, a flat spring wound around said pintle between said flanges with its inner end attached to the pintle to turn therewith, said bracket having a base provided with openings for 40 mounting the same to a door jamb, the outer end of the spring also having an opening and adapted to be anchored flat against the base by the means for mounting the base to the door jamb, said pintle having a lower 45 extension projecting through one of the flanges on the bracket and bored to permit the insertion of a spring-retaining member therethrough when adjusting the tension of said spring.

50 In testimony whereof I affix my signature.

JOHN T. HILL.
